UNITED STATES PATENT OFFICE.

ALFRED G. F. KUROWSKI, OF BROOKLYN, NEW YORK, ASSIGNOR TO UNDERWOOD TYPEWRITER COMPANY, OF NEW YORK, N. Y., A CORPORATION OF DELAWARE.

TYPEWRITING MACHINE.

Application filed March 8, 1923, Serial No. 623,622.

To all whom it may concern:

Be it known that I, ALFRED G. F. KUROWSKI, a citizen of the United States, residing in Brooklyn Borough, in the county of 5 Kings, city and State of New York, have invented certain new and useful Improvements in Typewriting Machines, of which the following is a specification.

This invention relates to typewriting machines. More particularly, the invention relates to sound-deadening devices for various parts of the mechanism of the machine.

In a typewriting machine, in which the platen is mounted in a frame shiftable on 15 the main frame of the machine between case positions, a feature of the invention is the provision of means for deadening the noise of impact of the platen-frame on its return to lower-case position on its seat on the 20 main frame, or on its seat on the carriage which has movement in letter feed and return directions on the main frame.

In the preferred form of the invention, the noise-deadening means, referred to, consist of springs at the front and rear of the platen-frame and at the sides thereof between the platen-frame and the side pieces of the carriage; the springs being leaf-springs folded in U-shape and having their 30 free ends held in partial compression by pins, carried by ears on the fixed portions of the springs, to determine the normal setting of the springs and normal or lower case position of the platen-frame; the rear 35 springs being affixed to the platen-frame and the front springs to the carriage side pieces.

A further feature of the invention is the provision of a cushion, preferably in the form of a spring, for deadening the noise of 40 impact of the platen-frame as the same is arrested in upper-case position, and of means for adjusting the setting of the cushion to the required upper-case position of the platen.

45 A feature of the invention is the provision of means for deadening the noise of impact of the shift-key lever against its stop on return of the lever to normal position.

In a machine in which a detent-arm is 50 engageable with a line-space ratchet-wheel for holding the platen in the position to which it has been line-spaced, and in which an arm or cam piece, preferably pivoted to swing around the axis of the platen, is provided to throw such detent clear of the

ratchet-wheel, and to hold the same clear of the ratchet-wheel, for rotary setting of the platen independent of the detent-device, a feature of the invention is the provision of means for preventing loose play of such 60 detent-controlling device and for deadening the noise of any movements thereof.

In a machine in which line-space movement of the platen is effected by a pawl-and-ratchet device, a feature of the invention is the provision of simple and reliable means for throwing the pawl clear of the ratchet preliminary to the return movement of the pawl to normal position, and for holding it 65 clear of the ratchet during such return 70 movement to prevent noise or rattle of the pawl on the ratchet.

Other features and advantages will hereinafter appear.

In the accompanying drawings,

75 Figure 1 is a view, in side elevation, taken at the left-hand side of the machine on the line 1—1 of Figure 2.

Figure 2 is a top plan view of the left-hand end of the carriage; the left-hand side plate of the platen-frame being partly broken away for disclosure of parts below the same.

Figure 3 is a view, in front elevation, taken on the line 3—3 of Figure 1.

85 Figure 4 is a perspective view of the device for disengaging the line-space pawl from the line-space ratchet wheel for returning the line-space mechanism to normal position; the spring forming part of the device being shown as separated from the rest of the device for clearer illustration.

The platen 10 is fast on an axle 11, journaled in the side plates 12 of a platen-frame shiftable up and down between case-positions on a carriage 13. Arms 14, pivoted at 95 15 on the carriage, engage pins 16 on the side plates 12 of the platen-frame to guide the latter in its movements between case-positions. The side plates of the platen-frame are connected and tied together at the rear by a bar 17, and at the lower part of the platen-frame by a rod or bar 18. A bracket 19, secured to the bar 18, carries a roller 20 supported on a rail 21 on a device which lifts the platen-frame from one case-position to another. This device comprises a pair of bell-cranks 22, which carry the rail 21 and which are pivoted to the main frame 23, at 24. The other arm 100 105 110

25 of one of the bell-cranks is engageable by the arm 26 of a bell-crank shift-lever fulcrumed on the main frame at 27. This lever comprises an arm 28, which extends forward to the keyboard 29, and at its forward end carries a shift-key 30. A coil-spring 31, engaging the under edge of the shift-lever, returns the same to normal position and holds the same up in normal position. Depression of the shift-key 30 causes the arm 26 to swing the shifter forward and upward; thus lifting the rail 21 and the platen-frame supported thereby. When the shift-key 30 is released, the platen-frame, unless locked, is returned by gravity to its original position, carrying the shifter with it. The carriage 13 has movement in letter feed and return directions on the main frame. For this purpose, it is supported at its rear on a rail 32, and at its front carries a roll 33, by means of which it is supported on a rail 34 on the main frame. The machine shown is a front-strike machine; one of the type-bars being indicated at 35.

In the normal or lower-case position of the platen-frame, the latter is supported at its rear on a pair of posts 36, one at each side of the carriage, and carried by the side pieces 37 of the carriage. As shown in Figures 1 and 2, the side plates 12 of the platen-frame have outturned flanges 38. Secured to each of these flanges, by screws 39, is a leaf-spring 40, which extends from its point of attachment forward, as at 41, and which is then turned on itself at 42, and folded back over the corresponding post 36 on the carriage. As the platen-frame drops by gravity to lower-case position, the springs 40 engage the tops of the posts 36 and serve to support the carriage on the posts. The springs 40 thus cushion the blow which the platen-frame would otherwise give the posts, and deaden the sound of such blows. The set of the leaf-springs is such that they are always under compression, with the parallel legs thereof tending to spread apart. This tendency of each spring is resisted, and the normal setting of the spring determined, by means of a pin 43, which projects under the lower free end of the spring, and which is carried by an ear 44 turned down from the forwardly-extending upper reach 41 of the spring.

The forward portion of the platen-frame, in the lower-case position of the latter, is supported by the side pieces 37 of the carriage. For this purpose (see Figures 1 and 2), the side plates 12 of the platen-frame, at their front ends, have inturned flanges 45. In the present invention, however, the lower edges of these flanges do not actually engage the carriage-pieces 37, but, in lower-case position, rest upon leaf-springs 46, secured by screws 47 to the carriage-pieces 37. These

springs extend from their point of attachment rearward along the carriage-pieces 37, and are then first turned forward, and then again rearward, in Z-shaped formation, terminating at their free ends 48 below the flanges 45 of the platen-frame. Like the springs 40, the springs 46 are under compression. Pins 49, overlying the upper reaches of the springs 46, determine the normal setting of the springs, and resist the expansion thereof beyond such normal setting. These pins 49 are carried by ears 50, turned up from the side edges of the lower reaches of the springs 46. As the platen-frame returns to lower-case position, the flanges 45 thereof engage the springs 46, and the latter, yielding downward, cushion the blow of such return movement. After the original yield of the springs 40 and 46, the same have a reflex action determined by the pins 43 and 49, so that the platen-frame assumes the normal position shown in Figure 1.

The throw of the platen-frame to upper-case position is determined by engagement of the upper edges of lugs 51, one on each side plate 12 of the platen-frame, with the free ends 52 of springs 53, secured to the side pieces 37 of the carriage. The springs 53 are leaf-springs, which are folded, at 54, at their forward portions, and have two legs 55 and 56. The upper leg 56 has its rearward free end turned down, at 57, to the upper surface of the lower leg 55, thus stiffening the free end 52 of the spring which receives the impact of the lug 51 on the platen-frame. The springs 53 are set into grooves 58 in blocks or lugs 59 on the carriage-pieces 37, and are held therein by the heads 60 of screws 61, which thread into the carriage side-pieces between the upper and lower legs of the springs. The grooves 58 are inclined downward and rearward, and, when the screws 61 are loosened, the springs may be shifted in either direction along the grooves to raise or lower the free ends 52 of the springs, and thus to adjust the upper-case position of the platen-frame. As the platen-frame comes to upper-case position, the lugs 51 strike the ends 52 of the springs, and the latter yield to cushion the blow, thus deadening the sound, and then have a reflex action to the normal setting, which is the upper-case position of the platen-frame.

The shift-key-levers, as well as the other key-levers, are ordinarily guided in a comb-plate supported by the front corner-posts of the main frame, and are arrested in upper normal position by this plate, after operation thereof. As hereinbefore stated, a feature of the invention is the deadening of the noise of impact of the shift-lever on the comb-plate or other stop on return to normal position. This is accomplished by means of a spring 62, secured by a screw 63

to the inner face of the corner-post casting 64; the casting being ordinarily of L-shaped horizontal cross-section. The spring may have a flange 65 thereon, turned over the 5 edge of the corner-post, to hold the spring against angular displacement. Below the screw 63, the spring is turned rearward from the inner face of the corner-post, and then forward, in the form of a U, terminating 10 in a tip 66 in vertical alignment with the upper edge of the shift-key-lever 28. As the latter is thrown upward by the spring 31, or by the gravity return of the platen-frame acting through the shifter and the 15 lever-arm 26, the upper edge of the shift-lever strikes the tip 66 of the spring 62, and the lever is thereby cushioned and its normal position determined.

A further feature has been stated to be the 20 provision of means for avoiding the noise or rattle of the line-space pawl on the line-space ratchet-wheel during the return of the line-spacing mechanism to normal position. The line-space mechanism shown in the 25 drawings is that ordinarily present in the Underwood standard typewriting machine. Briefly, it comprises a ratchet-wheel 67, fast to, or adapted to be made fast to, the platen-axle 11. The teeth of the ratchet-wheel are 30 engageable by the tooth 68 of a pawl 69, pivoted at 70 on a slide 71, mounted to have movement back and forth in a guideway on the left-hand plate 12 of the platen-frame. A coil-spring 72, connected at its rear end, 35 at 73, to the slide 71, and, at its front end, at 74, to a lug on the platen-frame, returns the slide, with the pawl thereon, to normal position. A bell-crank line-space lever, pivoted at 75 on the platen-frame, for angular movement in a horizontal plane, has one 40 arm 75a thereof in position to engage a flange or offset 76 at the forward part of the slide, to effect rearward line-spacing movement of the slide with the pawl, and has the other arm 77 thereof extended forward, with a finger-piece 78 on the end thereof, for operation of the line-space mechanism. The 45 spring 72 acts through the slide 71 to return the line-space lever to normal position after each line-spacing operation. The pawl 69 tends by gravity to drop and rest upon the top of the ratchet-wheel. This action is, 50 however, made more certain by means of a leaf-spring 79, attached at one end to the platen side-plate, and bearing at its free end 55 on the upper edge of the pawl. In the return movement of the slide with the pawl to normal position, the pawl therefore rests upon, or is pressed against, the teeth of the 60 ratchet-wheel, and, as it passes over the teeth, it creates objectionable rattle or noise. To avoid this noise, the pawl, at the outset of its return movement, is lifted clear of the 65 teeth of the ratchet-wheel by the device shown in Figure 4. This device consists of

an arm 80 on a hub 81, journaled on a hub or boss 82 which forms the extended bearing of the platen-axle at the left-hand side plate 12 of the platen-frame. The arm 80, near the end thereof, has a cam-slot 83 therein; 70 and into this cam-slot projects a pin 84 on the side face of the pawl 69 beyond the tooth 68 of the pawl. The shape of the slot is such as to guide the pawl down onto the ratchet-wheel, or at least to permit the pawl to drop 75 upon the ratchet-wheel, when the pawl-slide starts rearward, but to cam the pawl up clear of the ratchet-wheel when the slide starts forward in its return movement. The hub 81 of the arm 80 is journaled for angular 80 rearward and forward swing so as to participate in the movements of the pawl-slide, and not to obstruct such movements. In order, however, that the camming, referred 85 to, may take place, the pawl-slide, at the commencement of its movements rearward and forward, must have movement relative to the cam-arm 80; in other words, at such times, the cam-arm 80 should be held against its angular movement. This temporary 90 holding of the cam-arm is effected by means of a leaf-spring 85, riveted at 86 to the arm 80, and having its free end set into a groove or cut 87 which extends crosswise of the hub 81, through the latter, at such a depth 95 as to permit the spring 85 to bear upon the boss or hub 82 on the platen-frame, within the hub 81. The pressure of the spring 85 on the hub 82 is sufficient to hold the cam-arm 80 against angular movement until the 100 pin 84 on the pawl, after traveling the length of the slot 83, positively engages the arm at the other end of the slot. Thereupon, the spring 85 ceases to hold the arm 80, and the latter moves angularly, as above stated. 105 The camming effect of the slot 83 has, however, been attained while the arm 80 was held frictionally by the spring to the boss 82. The arm 80 being held by the spring 85, as the pawl-slide starts forward to normal position, the pin 84 on the pawl rides up the slot 83 to lift the pawl from the ratchet-wheel, whereupon, with the pawl 110 thus cleared of the ratchet-wheel, the arm 80 is rocked forward, holding the pawl in its elevated position. Upon rearward movement of the pawl, the slot 83 first guides the pawl into engagement with the teeth of the ratchet-wheel, and then, upon further rearward movement of the pawl, the arm 80 115 is carried therewith in the line-spacing operation.

In order that, line-spacing movement of the platen having been effected, the platen may be held against accidental displacement, a detent-device is ordinarily employed. This is shown as a roller 88, set into a yoke 89 on an arm 90, pivoted at 91 to the side plate of the platen-frame. A spring 92, bearing at one end against a pin 93 on the platen- 120

130

frame, is coiled around the pivot 91 of the arm 90, and at its other end 94 is turned over and bears against the rear edge of the arm 90, to hold the roller 88 resiliently to the ratchet-wheel. It is desirable at times that the platen be relieved of the detent-device so as to be revoluble and adjustable, independently thereof, relatively to the ratchet-wheel. For this purpose, there is employed 10 in the Underwood machine a cam-device consisting of an arm or plate 95, having a cam edge or surface 96 thereon for engagement with the roller 88 to throw the roller from the ratchet-wheel. The plate 95 is provided 15 with a yoke or semi-circular bearing 97, by means of which it may be journaled, for angular movement, on a hub 98 on the platen-axle. The arm or plate 95 carries a finger-piece 99, by means of which it may be swung 20 upward around the axis of the platen as a center, to cause the cam-edge 96 to throw off the arm 90 and roller 88 against the action of the spring 92. When the cam-plate is 25 thrown by the finger-piece to the Figure 1 position, it permits the roller 88 to be thrown by the spring 92 into contact with the teeth of the ratchet-wheel.

The drawings indicate, in a general way, the mechanism, more fully shown and described in U. S. Letters Patent to W. F. Helmond, No. 1,150,366, dated August 17, 1915, for permitting adjustment of the platen relatively to the ratchet-wheel, for releasing the platen for such adjustment, and 30 for positively holding the platen in any adjusted position. The ratchet-wheel 67 is fixed to the hub 98 of a clutch-member 100. Another clutch-member, not shown, but 35 shown in the Helmond patent referred to, is set within the clutch-member 100, and is 40 made fast to the platen-axle 11. The platen and its axle 11 turn freely with respect to the hub 98 of the clutch-member 100, and ratchet-wheel mounted thereon, until the inner clutch-member, not shown, is locked to 45 the clutch-member 100. After such locking, the platen may be rotated by means of the ratchet-wheel. When the clutch-members are 50 unlocked, the platen and platen-axle may be turned by means of a hand-wheel 101 on the end of the platen-axle. As shown in the Helmond patent referred to, a locking device 102, movable longitudinally of the 55 platen-axle, is employed for locking and unlocking the clutch-members.

As above stated, it is upon the hub 98 of the clutch-member 100 that the yoke or semi-circular bearing 97 of the detent-release device or cam-plate 95 is journaled. The pressure of the spring 92, acting through the detent-arm 90, on the periphery of the cam-plate may serve to hold the yoke or semi-circular bearing 97 of the latter on the hub 98. To prevent vibration of the yoke 97 60 onto and off of the hub 98, and to avoid the

noise of such vibration, the yoke 97 is shown as provided with a flange 103, which is set snugly, but revolubly, within a corresponding groove in the left-hand face of the ratchet-wheel. To prevent play of the yoke 70 97 longitudinally of the hub 98, and to prevent the noise due to such play, a leaf-spring 104 is riveted at 105 to the left-hand face of the cam-plate 95. This spring is branched to have prongs which extend along the 75 branches of the yoke. These prongs or branches of the spring, as shown at 106, are bent or bellied outward from the yoke intermediate their ends, so as to provide a bearing for the springs on the right-hand 80 face of the clutch-member 100. The spring 104 being thus compressed between the clutch-member 100 and yoke 97, the latter is held by the spring in its extreme right-hand position, against play longitudinally 85 of the hub, and with the flange 103 of the yoke within the groove in the face of the ratchet-wheel. In this manner, the cam-plate 95 is held against vibration in any direction, and noise from this part of the 90 mechanism is eliminated. The spring will yield to permit the yoke to be slid leftward sufficiently to clear the flange 103 of the ratchet-wheel, thus permitting removal of the cam-plate. Otherwise, as above noted, 95 the spring, by holding the flange 103 in the ratchet-wheel, provides positive interlocking of the ratchet-wheel and cam-plate 95 to prevent vibration in the plane of the cam-plate. 100

Variations may be resorted to within the scope of the invention, and portions of the improvements may be used without others.

Having thus described my invention, I 105 claim:

1. In a typewriting machine, a platen, a frame for the platen, a support for the platen-frame, means for shifting the platen-frame between case positions on its support, and a spring-seat for the platen-frame on 110 its support to cushion and sound-deaden the impact of the platen-frame against the support when the platen-frame is arrested in the movement thereof from one to another case position; the spring-seat comprising a folded leaf-spring secured to the platen-frame, and an abutment on the support for engagement with the free end of the leaf-spring, one reach of the leaf-spring having 115 an ear thereon and a pin on the ear for engagement with the other reach of the leaf-spring to hold the spring partially compressed and to determine the normal setting of the platen-frame on its support. 120

2. In a typewriting machine, a platen, a frame for the platen, a support for the platen-frame, means for shifting the platen-frame between case positions on its support, and a spring-seat for the platen-frame on its support to cushion and sound-deaden the im- 125 130

- pact of the platen-frame against the support when the platen-frame is arrested in the movement thereof from one to another case position; the spring-seat comprising a folded leaf-spring secured to the support, and means for holding the leaf-spring partially compressed to determine the normal setting of the platen-frame on its support. 5
3. In a typewriting machine, the combination of a platen, a frame therefor movable into upper and lower case-positions, a support for said frame, means for shifting said frame between case-positions, a spring on said support to cushion and sound-deaden 10 the impact of said frame against said support, and means for holding said spring under partial compression to determine the normal setting of said frame on said support. 15
- 20 4. In a typewriting machine, the combination of a platen, a frame therefor, a support for said frame, means for shifting said frame between case-positions, a folded leaf-spring on said support having a flat contact portion to engage said frame for sound-deadening the stoppage of said frame, and means for engaging said spring adjacent said flat contact portion to limit the expansion thereof and determine the normal setting 25 of said frame on said support. 30
5. In a typewriting machine, the combination of a platen, a frame therefor, a support for said frame, means for shifting said frame between case-positions, a leaf-spring 35 on said support folded to form parallel legs having a tendency to spread apart, one of said legs being located in the path of travel of said frame for sound-deadening its stoppage, and means for limiting the spreading 40 of said legs and thus determining the normal setting of said frame on said support. 45
6. In a typewriting machine, the combination of a platen, a frame therefor having a forward vertical flange and movable from one case-position to another, a carriage for supporting said platen having a forwardly-extending arm to limit the movement of said flange, means for shifting said frame from one case-position to another, and a spring on said arm for engaging said flange and cushioning and sound-deadening the impact of said flange on said arm. 50
7. In a typewriting machine, the combination of a platen, a frame therefor having a forward vertical flange and movable from one case-position to another, a carriage for supporting said platen having a forwardly-extending arm to limit the movement of said flange, means for shifting said frame from one case-position to another, a leaf-spring on said arm for engaging said flange and cushioning and sound-deadening the impact of said flange on said arm, and means for limiting the return movement of 55 60 65 70 75 80 85 90 95 100 105 110 115 120 125
- said spring after impact and thus determining the normal setting of said frame on the carriage. 65
8. In a typewriting machine, the combination of a platen, a frame therefor having an inclined rearward flange and movable from one case-position to another, a carriage for supporting said frame having a post thereon adjacent said flange, a leaf-spring secured to said flange and folded to form parallel legs having a tendency to separate, one of said legs engaging said post for cushioning the stoppage of said frame on its movement to a lower position, and means for limiting the spreading tendency of said legs and thereby determining the normal setting of said frame on said carriage. 75
9. In a typewriting machine, comprising a main frame and front corner posts, a platen, a platen-frame shiftable from a lower to an upper case position, a key-lever adjacent one of the front corner posts of the machine and depressible to shift the platen-frame to upper case position, means for returning the shift-lever to normal position, and a spring on the corner post adjacent the shift-lever for arresting the shift-lever in normal position, the spring being a leaf-spring turned inward from the corner post and then folded forward and having its free end in alignment with the upper edge of the shift-lever. 85
10. In a typewriting machine, comprising a main frame and front corner posts, a platen, a platen-frame shiftable from a lower to an upper case position, a key-lever adjacent one of the front corner posts of the machine and depressible to shift the platen-frame to upper case position, means for returning the shift-lever to normal position, and a spring on the corner post adjacent the shift-lever for arresting the shift-lever in normal position, the spring having an offset engageable with the side edge of the corner post to prevent angular displacement of the spring. 100
11. In a typewriting machine, the combination of a main frame having front corner posts, a platen, a frame therefor shiftable into upper and lower case-positions, a key-lever adjacent one of said front corner posts and depressible to shift said frame to upper case-position, means for returning said shift-lever to normal position, and a folded leaf-spring secured to said corner post and having a free end in alignment with the upper edge of the shift-lever for arresting it in normal position, said spring having also an offset engaged with the side edge of said post for preventing angular displacement of said spring. 115

ALFRED G. F. KUROWSKI.
